UNITED STATES PATENT OFFICE.

ROBERT H. KLINGEL, OF BRIDGEPORT, ASSIGNOR TO THE HOLMES & EDWARDS SILVER COMPANY, OF WEST STRATFORD, CONNECTICUT.

DESIGN FOR A SPOON, FORK, &c.

SPECIFICATION forming part of Design No. 18,315, dated May 15, 1888.

Application filed March 27, 1888. Serial No. 268,670. Term of patent 14 years.

To all whom it may concern:

Be it known that I, ROBERT H. KLINGEL, a citizen of the United States, residing at Bridgeport, in the county of Fairfield and State of Connecticut, have invented and produced a new and original Design for Spoons, Forks, &c.; and I do declare the following to be a full, clear, and exact description of the same, reference being had to the accompanying drawing, forming a part thereof.

The drawing is an elevation of a spoon embodying my novel design.

In outline the handle is narrowest at the shank. The lines of the sides of the handle are straight or slightly concave and diverge from the upper portion of the shank. The upper edge of the handle is an approximately circular curve. At the extreme upper end of the handle is a bead, denoted by 1, which forms the outer edge of a crescent-shaped depressed panel, 2. The surface of the panel is ordinarily roughened or frosted, and is ornamented by a series of raised oval figures, 3, which are largest at the center and diminish in size in both directions, the series ending in the horns of the crescent. Below the crescent-shaped panel and well down toward the shank the handle is perfectly plain. The lower portion of the handle and the upper portion of the shank are ornamented by a set pattern, which I will now describe. At about the center thereof is a conventional figure of a rosette, denoted by 4, upon a roughened or frosted groundwork. Above and below the rosette are cross-bars. On the upperside, be-

tween one pair of cross-bars, is a row of raised dots extending across the handle. Above the upper cross-bar is a series of divergent lines intersecting other lines which extend inward from the sides of the handle and upward toward the upper end, meeting at the center, thereby forming a triangle with slightly concave sides. Between two of the cross-bars below the central rosette is a series of X's extending across the handle. Below the lower cross-bar are two triangular figures pointed downward, and below these figures another rosette, denoted by 5.

I claim—

The design for the ornamentation of handles of spoons, forks, &c., herein shown and described, the same consisting, essentially, of a crescent-shaped panel at the upper end, oval figures on said panel, largest in the center and diminishing in size toward the horns of the crescent, below the crescent-shaped panel a perfectly plain surface, and upon the lower portion of the handle and upper portion of the shank a set figure consisting, essentially, of a rosette, 4, cross-bars above and below the rosette, divergent lines above the rosette intersecting other lines extending inward and upward from the sides, and triangular figures below the rosette pointed downward.

In testimony whereof I affix my signature in presence of two witnesses.

ROBERT H. KLINGEL.
